UNITED STATES PATENT OFFICE.

VALENTINE GEORGE BARFORD, OF BASINGSTOKE, ENGLAND, ASSIGNOR TO JOHN I. THORNYCROFT & CO., LIMITED, OF WESTMINSTER, ENGLAND.

APPARATUS FOR SUPPLYING LIQUID FUEL TO INTERNAL-COMBUSTION ENGINES.

1,263,839.

Specification of Letters Patent. Patented Apr. 23, 1918.

Application filed August 24, 1916. Serial No. 116,749.

To all whom it may concern:

Be it known that I, VALENTINE GEORGE BARFORD, a subject of the King of Great Britain and Ireland, residing at Basingstoke, in the county of Hants, England, have invented Improvements in Apparatus for Supplying Liquid Fuel to Internal-Combustion Engines, of which the following is a specification.

10 This invention relates to means or apparatus for supplying liquid fuel to internal combustion engines and it has for its object to provide a liquid fuel pump and controlling means therefor whereby the amount of 15 liquid fuel supplied to an engine can be controlled in a simple, easy and effective manner and, in the event of the fuel delivery pipe becoming obstructed for any reason, to enable the liquid fuel to be delivered back 20 from the pump into the liquid fuel supply pipe or receptacle.

In means or apparatus according to the invention the pump chamber is provided with a loaded relief valve and the inner end 25 of the pump plunger is so shaped that, by rotation of the plunger about its axis, it can, during its inward stroke, be caused to open the relief valve earlier or later, or not to open such valve, and in this way vary the 30 amount of liquid fuel delivered to suit the varying requirements of the engine to which the liquid fuel is supplied. Conveniently, the inner end of the pump plunger may be made of spiral or helical shape and arranged 35 to act endwise on its inward stroke and open a spring loaded relief valve arranged with its axis eccentric to that of the plunger. The plunger may conveniently be rotated at the required times and to the required extent 40 from the engine governor so that the supply of liquid fuel will be controlled automatically according to the load on the engine, but the plunger can be rotated or adjusted by hand if desired. The stroke of 45 the plunger is normally constant but is capable of adjustment for varying the maximum amount of liquid fuel capable of being delivered at any time, the shaped inner end of the plunger and the relief valve acting as 50 variable cut off means for determining the point at which the delivery of liquid fuel from the pump shall cease.

Liquid fuel supply apparatus adapted to operate in the manner described can be variously constructed and arranged.

In the accompanying drawings, Figure 1 is an elevation and Fig. 2 a plan, both partly in section, of one arrangement of such apparatus. Fig. 3 is a vertical section corresponding to the line A B of Fig. 1 and 60 looking at the latter from the left hand side.

According to this example the pump comprises a casting *a* that is bored to receive a stationary sleeve *b* in which the plunger *c* can work endwise and also rotate. The inner end of the bore is enlarged to form an eccentrically arranged pump chamber *d* which is closed at the opposite end by a screw plug *e* provided with an axially arranged relief passage *f* communicating with 65 a number of radial relief passages *g* and controlled by a loaded relief valve *h*. In the casting *a* and parallel, it may be, and as shown, to the bore containing the sleeve *b* and pump plunger *c*, is a second bore or 70 passage *a*¹ open at both ends. One end portion of this bore or passage is fitted with a bush *i* having a seat for a spring loaded suction valve *j* while the other end of the said bore is closed by a tubular screw plug *k* that is provided with a spring loaded delivery valve *l* and is adapted to be connected 75 to an oil delivery pipe *m*. At a point between the two valves *j* and *l*, which may be ball valves, as shown, the second bore *a*¹ is 80 connected by a passage *n* to the pump chamber *d*. The inner end of the pump plunger *c* is provided with a spiral or helical shaped abutment or cam surface *o* co-axial with the plunger and the relief valve *h* is provided 85 with a stem *p* extending into the pump chamber *d* and into the path of the said abutment surface *o*. Secured below the screw plug *e* carrying the relief valve *h* and 90 the end of the second bore *a*¹ controlled by the suction valve *j* is a receptacle *r* to which liquid fuel is supplied. The pressure of the liquid fuel should be such as to overcome the spring pressure on the suction valve *j* when 95 the pump plunger *c* makes its suction stroke 100 in order to prevent the continuity of the liquid fuel being broken should the fuel be hot or contain constituents which easily vaporize at ordinary temperatures and pressures. The relief valve *h* is normally 105 pressed against its seat in the plug *e* by a coiled spring *s* located within a hollow extension *e*¹ of the plug, its action being capable of adjustment by means of a cap *t*, screwed on the end of the extension *e*¹ and 110

capable of being locked in place by a nut *u*. The relief valve *h* not only serves to govern or control the amount of liquid fuel delivered from the pump as described, but it also 5 serves to permit the liquid fuel entering the pump chamber *d* to be delivered back into the supply receptacle *r* in the event of any 10 obstruction taking place on the delivery side of the pump. The spring *s* for this valve is therefore set at that pressure which corresponds to the maximum desirable pressure 15 in the pump and connected delivery pipe.

At a part outside the pump casting, the plunger *c* is provided with a pinion *v* between which and the casting is a coiled spring *w* for effecting the outward stroke of the plunger. In gear with the pinion *v* is a part circular rack *x* fixed to a spindle *y* mounted in a bearing *z* and provided at 20 its other end with a crank pin or handle 1 for operation from a governor, or by hand, as found most convenient in any particular case. The inward stroke of the plunger *c* is effected by an arm 2 that is 25 mounted to rock and act at the required times against the outer end of the plunger and is operated through a shaft 3 in any convenient way, as by a lever 4 and rod 5 from an eccentric on the crank shaft of the 30 engine.

The extent of the outward travel of the pump plunger *c* can be controlled by means, such as an adjustable cam 6, arranged to act against the outside of the pinion *v* and 35 operated from a shaft 7.

With the arrangement described it will be understood that the relief valve *h* will be forced open by cam-shaped inner end *o* of the plunger *c* earlier or later during the 40 inward stroke of the pump, according to the extent to which the plunger has been rotated, and in this way control the quantity of liquid fuel delivered by the pump to the engine.

45 Two or more pumps such as described can be used and governed simultaneously by the same governing means and their plungers operated by a rocking arm or arms in the way described. Thus, in the drawings, the 50 parts described and lettered are duplicated, 8 representing a rod connecting together a pair of crank arms 9 provided for the simultaneous operation of the plunger cam stops 6 of both pumps. The method of governing 55 described can however be applied to pumps the plungers of which are reciprocated by equivalent means to those hereinbefore described.

Apparatus such as described can be used 60 with two or four stroke cycle engines.

What I claim is:—

1. Apparatus of the kind herein referred to comprising a pump chamber, valve means controlling the inlet and outlet of liquid to 65 and from said chamber, a plunger adapted

to draw liquid into said chamber under control of said valve means, a relief valve and means associated with the inner end of said plunger and whereby said relief valve can be opened at a definite point in the delivery 70 stroke of said plunger.

2. Apparatus of the kind herein referred to comprising a pump chamber, valve means controlling the inlet and outlet of liquid to and from said chamber, a plunger adapted 75 to draw liquid into said chamber under control of said valve means, a relief valve and adjustable means located within said pump chamber and whereby said relief valve can be opened at a definite but alterable point 80 in the delivery stroke of said plunger.

3. Apparatus of the kind herein referred to comprising a pump chamber, valve means controlling the inlet and outlet of liquid to and from said chamber, a plunger adapted 85 to draw liquid into said chamber under control of said valve means, a relief valve and adjustable means located within said pump chamber and under the control of the inner end of said plunger and whereby said relief valve can be opened at a definite but alterable point 90 in the delivery stroke of said plunger.

4. Apparatus of the kind herein referred to comprising a pump chamber, valve means 95 adapted to admit liquid to such chamber, a plunger adapted to draw a definite amount of liquid through such valve liquid delivery means and a relief valve having a part thereof extending into said pump chamber 100 and into the path of said plunger and to be opened by the inner end of said plunger at a definite but alterable point in its delivery stroke.

5. Apparatus of the kind herein referred to comprising a pump chamber, valve means adapted to admit liquid to such chamber, a loaded relief valve adapted to allow part of the admitted fluid to pass back to the supply and a pump plunger adapted by end- 110 wise motion to open the valve and by rotation to determine the point in the stroke at which such opening shall occur, if at all.

6. In apparatus of the kind herein referred to the combination with a pump 115 chamber, of a relief valve, a reciprocating plunger means associated with the inner end of said plunger and capable of opening the said valve during some part of the delivery stroke of said plunger and means for timing such opening of the relief valve.

7. In apparatus of the kind herein referred to the combination with a pump chamber, of a reciprocating plunger having a cam shaped inner end, a relief valve 125 adapted to be engaged by the said plunger end and movable along an axis eccentric to that of the plunger and means for rotating the plunger to vary the control exerted by the plunger upon the relief valve. 130

8. In apparatus of the kind herein referred to the combination with a pump chamber, of a reciprocating plunger having a cam shaped inner end, a relief valve adapted to be engaged by the said plunger end and movable along an axis eccentric to that of the plunger, means for rotating the plunger to vary the control exerted by the plunger upon the relief valve and means for adjusting the stroke of the plunger.

9. Apparatus of the kind referred to comprising a casting bored with two parallel passages, a passage connecting such bores, a fuel receptacle with which both bores communicate, a suction valve and a delivery valve associated with one bore, a plunger and a relief valve associated with the other bore, and means for angularly adjusting the plunger the said plunger and relief valve being independently movable along axes out of alinement and the end of the plunger being shaped to impart opening movement to the relief valve at different points in the delivery stroke in accordance with angular adjustment of the plunger, while the relief valve is free to open automatically with abnormal pressure in the pumping system each opening movement of the relief valve resulting in a return of fuel which has passed the suction valve to the said fuel receptacle.

10. In apparatus of the kind herein referred to, a pump plunger having a helical shaped end constituting a valve operating abutment.

11. Apparatus of the kind referred to comprising a casting bored with two parallel passages, a passage connecting such

bores, a fuel receptacle with which both bores communicate, a suction valve and a delivery valve associated with one bore, a plunger and a relief valve associated with the other bore, a toothed pinion on said plunger, a toothed quadrant gearing into said pinion, and means for moving said quadrant to angularly adjust said plunger, the said plunger and relief valve being independently movable along axes out of alinement and the end of the plunger, being shaped to impart opening movement to the relief valve at different points in the delivery stroke in accordance with angular adjustment of the plunger, while the relief valve is free to open automatically with abnormal pressure in the pumping system each opening movement of the relief valve resulting in a return of fuel which has passed the suction valve to the said fuel receptacle.

12. In apparatus of the kind herein referred to the combination with each of a pair of pump chambers, of a reciprocating plunger having a cam shaped inner end, a relief valve adapted to be engaged by the said plunger end and movable along an axis eccentric to that of the plunger and means for simultaneously rotating both of said plungers to vary the control exerted by the said plungers upon the said relief valve.

Signed at Winchester, in England, this 28th day of June, 1916.

VALENTINE GEORGE BARFORD.
